Primary Examiner — Samantha Q Lawrence(74) *Attorney, Agent, or Firm* — Taft Stettinius &
 Hollister LLP; Gerald E. Helget(57) **CLAIM**

The ornamental design for a reinforced pinned dowel composite stud for buildings, as shown and described.

DESCRIPTION

FIG. 1 is a left side perspective view of the reinforced pinned dowel composite stud for buildings;

FIG. 2 is a left side elevational view;

FIG. 3 is a front elevational view;

FIG. 4 is a right side elevational view;

FIG. 5 is a rear elevational view;

FIG. 6 is a top plan view along lines 6-6 of FIG. 4;

FIG. 7 is a bottom plan view along lines 7-7 of FIG. 4;

FIG. 8 is an enlarged top plan view thereof; and,

FIG. 9 is a cross sectional view taken along lines 9-9 of FIG. 2.

The broken lines shown in FIG. 8 illustrates environment of the reinforced pinned dowel composite stud for buildings that forms no part of the claimed design.

The reinforced pinned dowel composite stud for buildings is shown with a symbolic break in length. The appearance of any portion of the article between the break lines forms no part of the claimed design.
